UNITED STATES PATENT OFFICE.

WILLIAM P. CONLEY, OF CHICAGO, ILLINOIS.

VAPOR BURNER.

Application filed May 19, 1923. Serial No. 639,992.

The invention relates to vapor burners, and particularly to devices of this character which generate the vapors to be ignited through the medium of the heat created by the burning of the gases generated.

The invention has among its various objects the combination of certain elements which, when associated with each other, provide a compact and portable structure or stove suitable for homes, for travelers, or for use by campers, or others, in preparing food or heating other commodities.

The invention has among other objects the provision of an arrangement whereby the flames produced by the combustion of the gases created will be caused to spread as they emanate from the burner and thus act upon substantially the entire under surface of the vessel in which the commodity to be cooked or heated is confined.

It is another object of the invention to arrange a means adjacent the burner which will augment the distribution of the flames and thereby increase the heating capacity of the device.

It is a feature of the invention to construct the heater so that it may be readily assembled and disassembled when this is found necessary or desirable.

It is another object of the invention to provide a structure such as that referred to above with a means in which a small quantity of some volatile liquid, such as alcohol, may be placed, which, when ignited, causes the initial vaporization of a similar liquid confined in a reservoir. The heat created by the burning of the gases generated in the reservoir heats the container forming the reservoir and causes a continuation of the vaporization of the liquid contained therein.

It is a feature of the invention to provide a support for the various elements of the structure and to provide vents through which air may pass and cause the proper combustion and distribution of the flames caused by the burning of the gases.

It is another object to provide a structure which will reduce any vortex or similar action such as will cause the flames emanating from the burner to be attracted toward the center of the burner.

The invention will be explained in detail and more readily understood when read in conjunction with the accompanying drawings, which illustrate various embodiments of which the invention is susceptible, it be-

ing obvious that changes and modifications may be made without departing from the spirit of the appended claims forming a part hereof.

In the drawings:

Figure 1 is a side elevation of the structure showing the parts in assembled relation.

Figure 2 is a central section of the structure shown in Figure 1.

Figure 3 is a plan view of the grate employed in the structure.

Figures 4 and 5 are plan views of burners which may be employed in conjunction with the structure illustrated in Figure 1, and

Figure 6 is a central section of a burner such as shown in Figure 5.

The structure whereby the various features and advantages of the invention are accomplished includes a base 10 which is of a flared, annular outline having a plurality of apertures 11, 11 provided throughout its circumference adjacent the lower end thereof. Air for combustion purposes and for cooling the table or support and the lower portion of the base 10 is supplied through the apertures. A pan-shaped vessel 12 is fitted into the upper end 13 of the base 10.

The bottom of the vessel 12 is provided with a centrally arranged depression 14 which is provided to receive the cup-shaped container 15, and is further formed to provide an annular depression 16 which is separated from the depression 14 by the annular ridge 17. The depression 16 is employed for the purpose of providing a reservoir for a small quantity of some volatile liquid, such as alcohol, which when ignited, causes the initial vaporization of the liquid 18 confined in the container 15. The vessel 12 is provided with a plurality of apertures 19, 19 arranged at suitable intervals throughout the circumference thereof, adjacent the annular depression 16 which are provided to allow air to circulate therethrough from the interior of the base 10 into the interior of the vessel 12 and cause the flames resulting from the burning liquid confined in the recess 16 to be directed toward the container 15 until this liquid is consumed.

These apertures will, in addition, after the liquid in the recess 16 is consumed, cooperate and act to cause the flames emanating from the cup-shaped container cap or burner 20 to be spread outwardly relatively to said burner. The ves-

sel 12 is provided with an annular bead 21 which maintains the vessel in proper position relatively to the base 10.

The container 15, as before stated, is provided with the cap or burner 20 which fits the container 15 sufficiently tight to prevent the escape at the juncture of the cap and body portion of the container of any of the gases generated in said container.

- 10 The burner is further provided with an annular recessed portion 22 which causes a portion of the air entering the apertures 19 of the vessel 12 to be deflected outwardly relatively to the burner and container which 15 causes the flames emanating from the burner 20 to spread outwardly therefrom. The upper wall 23 of the burner is convexed and is provided with a plurality of annularly arranged apertures 24 and 25, the innermost series or row of apertures being 20 less in number than the outer.

The vessel 12 is further provided with a plurality of apertures 26 which are arranged adjacent its uppermost edge, and act to 25 cause the flames emanating from the small quantity of liquid in the depression 16 and the burner 20 to be inclined inwardly.

A spider generally designated 27, adapted to be removably mounted upon the upper 30 end of the vessel 12, is also employed and is supported by means of the supports 28 which are disposed at intervals below said spider and are designed to maintain the spider in spaced relation to the structure arranged below it. The spider 27 is composed of a plurality of radially arranged ribs 29 which are connected together by means of the annular connectors 30 and 31. The spider 27 has a wire mesh 32 secured to it 35 which is disposed below the ribs 29 so that said wire mesh will be arranged above the burner 20. The wire mesh is provided with a number of downwardly projecting aprons 33, 33, as shown, which are interposed between the burner 20, container 15, and the vessel 12. This mesh 32 with its aprons 33 acts to break up and distribute the flames emanating from the burner, becomes heated and thereby increases the heating capacity 40 of the device. The wire mesh is constructed and located in such a manner with respect to the burner and its flames that the heating is enhanced rather than retarded.

45 By arranging the apertures 24 and 25 in the manner shown and described, that is, toward the periphery of the cap or burner, and leaving the center of the burner blank or devoid of any apertures the vortex action usually occurring at this portion of the burner is substantially reduced. The vortex action usually causes the flames emanating from the burner to be drawn toward the center thereof and prevents the 50 spreading of the flame.

65 The structure illustrated in Figures 5 and

6 discloses another means whereby this vortex action may be reduced. The means therein disclosed employs a cup shaped container having a cap or burner 34 which has a concave depression 35 which will act upon the heated air at the center of the burner 70 and cause it to be directed outwardly relatively to the burner and cause the flames due to the ignition of the gases escaping through the annular rows of apertures 36, 75 37 and 38 to be directed toward the outer periphery of the burner. In view of the fact that the burner 34 is provided with the annular curved or recessed portion 39 the air striking this surface will also be deflected toward the outer edge of the burner, thus further insuring the spreading of the flames emanating from the burner.

From the foregoing description of the structure it is manifest that an arrangement is provided whereby the initial generation of a volatile gas may be readily accomplished. It is further evident that the generation of the gas will automatically take place after the gas created is ignited 85 and, further, that the possibility of any vortex action taking place at the center of the burner will be substantially reduced, causing the flames to be spread outwardly from the burner, all of which cooperate 90 to augment the efficiency of the structure.

Having thus described the invention what is claimed is the following:

1. In a device of the character described, the combination of a generator having a 100 burner, a vessel on the bottom wall of which said generator is adapted to be arranged, said vessel having a recess for the purpose of containing liquid which, when ignited, causes the initial operation of the generator, said vessel having apertures surrounding said 105 generator and above the bottom wall of said generator for directing the flames created by the ignition of said liquid in said recess to be directed toward said generator. 110

2. In a device of the character described, the combination of a member, a generator arranged therein upon the bottom wall of 115 said member, said member having a recess in which liquid may be contained which, when ignited, causes the initial operation of said generator, said generator having a burner having means for causing the flames emanating from the burner to be directed toward the outer edge of said burner, said member having apertures surrounding said 120 generator and above the bottom wall of said generator for directing the flames caused by the ignition of the liquid in said recess toward the generator. 125

3. In a device of the character described the combination of a container providing a generator, said container having a burner, the side wall of the container being formed to provide an annular curved portion located 130

adjacent the top of the container, said annular curved portion being flared outwardly beyond the side wall of said container for causing the flames emanating from said 5 burner to be directed toward the periphery of the burner, having a semi-spherical imperforate depression arranged concentrically with relation to the periphery of the top of the burner.

10 4. In a device of the character described the combination of a container providing a generator, said container having a burner, the side wall of the container being formed to provide an annular curved portion located 15 adjacent the top of the container, said annular curved portion being flared outwardly beyond the side wall of said container for causing the flames emanating from said burner to be directed toward the periphery 20 of the burner, having a semi-spherical imperforate depression arranged concentrically with relation to the periphery of the top of the burner and having rows of concentrically arranged perforations disposed adjacent the periphery of the top of the burner.

5. In a device of the character described the combination of a container providing a generator, said container having a burner, the side wall of the container being formed to provide an annular curved portion located adjacent the top of the container for causing the flames emanating from said burner to be directed toward the periphery of the burner, the top of said burner having 30 a central imperforate portion, and having rows of concentrically arranged perforations disposed adjacent the periphery of the top of the burner, the number of said perforations in the outer row being greater than 35 those of the inner rows.

40 6. In a device of the character described the combination of a container providing a generator, said container having a burner, the side wall of the container being formed to provide an annular curved portion located adjacent the top of the container, said annular curved portion being flared outwardly beyond the side wall of said container for causing the flames emanating from said 45 burner to be directed toward the periphery of the burner, a central imperforate portion on the top of the burner, a semi-spherical imperforate depression arranged concentrically with relation to the periphery of the 50 top of the burner and within said central imperforate portion, and having rows of concentrically arranged perforations disposed adjacent the periphery of the top of the burner, the number of said perforations 55 in each row progressively increasing toward the periphery of the top of the burner.

60 7. In a device of the character described the combination of a cup-shaped vessel, across the open end of which a grate is 65 adapted to be arranged, a container in

which a quantity of liquid may be confined, said container having a perforated top, and providing a generator, and being substantially smaller in diameter than the vessel, said container being arranged within and supported on the bottom of the vessel, and producing an annular space between it and the vessel which surrounds the container, the side wall of the vessel being provided with apertures which are disposed around the circumference thereof, above the bottom of the container in which the liquid is confined.

70 8. In a device of the character described the combination of a cup-shaped vessel, across the open end of which a grate is adapted to be arranged, a container providing a gas generator, in which a quantity of liquid may be confined, said container having a burner having a perforated top, 80 and said container being substantially smaller in diameter than the interior of the vessel, and being arranged therein so as to provide an annular space between it and the side wall of said vessel, said container being supported on the bottom of the vessel and extending from the bottom of the vessel to adjacent the top thereof, apertures provided in the side wall of the vessel and disposed circumferentially of the vessel above 85 the bottom thereof to thereby provide an annular portion which surrounds the container for the reception of a liquid which, when ignited, causes the initial operation of 90 said gas generator, said apertures being disposed above the bottom of the container in which the liquid is confined.

9. In a device of the character described the combination of a cup-shaped vessel, across the open end of which a grate is 105 adapted to be arranged, the bottom of said vessel being provided with a centrally disposed recess surrounded by an upwardly projecting annular rib which cooperates to produce a recess which surrounds said centrally disposed recess, apertures provided in the side wall of the cup-shaped vessel, said apertures being disposed around the circumference of the vessel adjacent the bottom 110 thereof above said second-mentioned depression, a container having a perforated top, said container being adapted to be arranged in the centrally arranged recess and providing a wall of an annular space which 115 surrounds the container.

10. In a device of the character described the combination of a cup-shaped vessel, across the open end of which a grate is adapted to be arranged, the bottom of said vessel being provided with a centrally disposed recess surrounded by an upwardly projecting annular rib which cooperates to produce a recess which surrounds said centrally disposed recess, apertures provided in 125 the side wall of the cup-shaped vessel, said 130

- 1 apertures being disposed around the circumference of the vessel adjacent the bottom thereof above said second-mentioned depression, a container having a perforated
- 5 top, said container being adapted to be arranged in the centrally arranged recess and providing a wall of an annular space which surrounds the container, and an apron extending from the grate into the vessel.
- 10 11. In a device of the character described the combination of a cup-shaped vessel, across the open end of which a grate is adapted to be arranged, the bottom of said vessel being provided with a centrally disposed recess surrounded by an upwardly projecting annular rib which cooperates to produce a recess which surrounds said centrally disposed recess, apertures provided in the side wall of the cup-shaped vessel,
- 15 said apertures being disposed around the circumference of the vessel, adjacent the bottom thereof above said second-mentioned depression, a container having a perforated top, said container being adapted to be arranged in the centrally disposed recess and providing a wall of an annular space which
- 20 surrounds the container, and a wire mesh
- 25
- extending across the top of the generator and having aprons which extend into the space produced between the generator and the vessel.
12. In a device of the character described, the combination of a cup-shaped vessel, across the open end of which a grate is adapted to be arranged, the bottom of said vessel being provided with a centrally disposed recess surrounded by an upwardly projecting annular rib which cooperates to produce a recess which surrounds said centrally disposed recess, apertures provided in the side wall of the cup-shaped vessel, said apertures being disposed around the circumference of the vessel adjacent the bottom thereof above said second-mentioned depression, a container having a perforated top, said container being adapted to be arranged in the centrally disposed recess and providing a wall of an annular space which
- 30 surrounds the container, and an apron extending from the grate into the vessel.
